(57) **CLAIM**

The ornamental design for a writing implement with attachments, as shown and described.

DESCRIPTION

FIG. 1 is a perspective view of a writing implement with attachments;

FIG. 2 is a front elevational view thereof;

FIG. 3 is a left side view thereof;

FIG. 4 is a right side view thereof;

FIG. 5 is a rear elevational view thereof;

FIG. 6 is a top plan view thereof; and,

FIG. 7 is a bottom plan view thereof.

The broken lines showing indicia on the attachments on the top in FIGS. 1-5 and the central parts of the top in FIG. 6 form no part of the claimed design.
